UNITED STATES PATENT OFFICE.

SAMUEL RUSSELL, OF BROOKLYN, NEW YORK, ASSIGNOR TO THE NATIONAL TELEPHONE COMPANY, OF HARTFORD, CONNECTICUT.

TRANSMITTING-TELEPHONE.

SPECIFICATION forming part of Letters Patent No. 240,041, dated April 12, 1881.

Application filed January 12, 1880.

To all whom it may concern:

Be it known that I, SAMUEL RUSSELL, of Brooklyn, in the county of Kings and State of New York, have invented certain Improvements in Transmitting-Telephones, of which the following is a specification.

My invention relates to what are known as "battery-transmitters," and has for its object to increase the fidelity and volume of the transmitted sounds.

In the drawings, Figure 1 is a vertical mid-section of my improved transmitter. Fig. 2 is a plan of the same. Fig. 3 is a fragmentary view, showing the electrode-connections. Figs. 15 4, 5, and 7 illustrate modifications, and Fig. 6 is a fragmentary detail view of the diaphragm-clips.

Let A represent the supporting block or case; B, a frame or bridge fixed to the back 20 thereof; C, the mouth-piece formed in the front thereof; D, the diaphragm, and E F the resistance-varying electrodes or contact-points. The electrode E is fixed to the back of the diaphragm and borne thereby, and the electrode 25 F is sustained by a spring or springs, b, which act to press the electrode F lightly against the electrode E, this pressure being adjustable. The action is to produce undulations in a battery-current passed through the contacts, 30 which undulations correspond to the vibrations of the diaphragm, in the manner common to all transmitting-telephones.

I have thus far described only the common form of battery-transmitter, to which I lay no 35 claim, and I will now set forth my novel improvements thereon.

The electrode F is borne by a spring or springs, b, which are fixed to a slide, c, (being a sliding plunger or frame,) which is arranged 40 to slide in bearings in the frame B in a direction toward or from the diaphragm. For adjusting the pressure of the electrode F against the electrode E, I provide a lever, e, fulcrumed to the frame B, engaging the rod c, and its extremity depressed by a thumb-screw, f, against the upward pressure of a spring, g. By this means a very accurate adjustment can be given to the electrodes.

In Figs. 4 and 5 I have shown two modifications of the adjusting device, which may be substituted for that shown in Fig. 1 if pre-

ferred. Fig. 5 shows a differential screw, f, which imparts vertical motion to a screw-threaded rod, c, which is fixed to a sliding cross-head, c', whereby it is held from revolving, and to this cross-head is attached a leaf-spring, b, which bears the cup a. Fig. 4 shows a horizontal screw, f, which engages a threaded sleeve or female screw forming the top of the electrode-bearing slide c. The contacting surfaces of the electrodes F and E are beveled, so that the lateral movement of the former on the latter will press them closely together.

Heretofore it has been common to incase the edge or periphery of the diaphragm in a rubber ring which extends down over both faces for a short distance, and then to place it in a shallow recess in the rear face or side of the block A, and fasten it therein by means of clips similar to those marked h h in Figs. 2 and 6. 65 By this means nearly all vibration at or near the edge has been deadened, which, as I believe, has materially impaired its ability to transmit sounds with the desired power and clearness. To overcome this defect I fasten 70 the diaphragm at as few points as possible—say three or four—and leave it free to vibrate in the spaces between the clamping-points. I take short strips i i, of rubber or analogous material, and bend them over the edge of the 80 diaphragm at intervals, then place the diaphragm in the recess and screw down the clips h h over the rubber strips, as best shown in Figs. 2 and 6. Thus at each clamping-point the edge of the diaphragm is confined between 85 two elastic cushions.

I am aware that a diaphragm has been heretofore confined at a series of points around its edge; but the means of clamping have consisted of naked metal surfaces, which practically prevent all vibration of the diaphragm at the clamping-points, besides causing the generation of extraneous and confusing sounds, resulting from the friction of the diaphragm against the edges of the metal.

In order to control to some extent the amplitude of the vibrations of the diaphragm, whereby any timbre or sympathetic sound peculiar to itself may be suppressed, I provide an adjustable damper, which I will now describe.

Referring to Fig. 1, H is a leaf-spring, fixed

at one end to some stationary part, and at the other end arranged in contact with a depressing-screw, I. At about its middle the spring H is curved toward the center of the dia-
5 phragm, and between the two is placed an an-
nular pad or washer, J, of rubber or other
elastic material. The electrode E projects up
through the central opening in the pad J, and
through a corresponding aperture formed in
10 the spring H. By turning the screw I the
pressure of the spring H upon the pad can be
adjusted. If preferred, an adjusting-screw, I,
may be arranged at each end of the spring.

In Fig. 7 the spring H is shown attached to
15 the block A, instead of to the frame B; and in
Fig. 4 an O-shaped spring is shown, its ends
brought nearly together and fixed to the top
of the frame B, and having two adjusting-
screws, I I, arranged horizontally in the sides
20 of the frame B. By causing the screws I I to
approach each other the center of the spring
H is forced down upon the pad J.

I am aware that in a transmitting-telephone
25 having two parallel diaphragms with the re-
sistance-varying device between them springs
have been arranged to press against a rubber
cushion on the center of each diaphragm, in
order to hold the latter in place, the spring
connected with the mouth-piece diaphragm
30 being incapable of adjustment, and the other
spring being adjustable by means of a screw,
(similarly to my modification shown in Fig. 7,) in
order to regulate the tension upon the re-
sistance-varying device; but I am not aware
35 that such spring and cushion have been em-
ployed in a telephone for muffling the vibra-
tions of the mouth-piece diaphragm, for which
purpose I consider it essential that the press-
ure of the spring shall be adjustable. In the
40 telephone referred to the entire edge of the
diaphragm is held against a continuous cush-
ion, instead of being supported at intervals
only, as in mine, in which latter case the em-
ployment of the damper is specially desirable.

45 I do not, in this application, make any spe-
cific claims to the forms of my invention shown
in Figs. 4 and 5, but reserve to myself the
right to make these the subjects of separate
applications for patents hereafter.

50 I claim as my invention—
1. A telephone wherein the diaphragm is

confined at separate points around its periph-
ery between two layers of elastic material,
leaving the intervening portions of its edge
unsupported and free to vibrate, substantially
as and for the purposes set forth. 55

2. In a transmitting-telephone, the combi-
nation of the diaphragm D, the electrode E
borne thereby, the electrode F fixed in a hold-
er, a, with the springs b and adjustable slide 60
c, arranged behind said electrode, substan-
tially as set forth.

3. The combination, in a transmitting-tele-
phone, of the supporting-block A, the dia-
phragm D fixed thereto, the electrode E borne 65
thereby, the electrode F fixed in the holder a,
the frame B, the slide c, suitable means for
adjusting it, and the bearing-springs b con-
necting said holder a to said slide c, substan-
tially as set forth. 70

4. The combination, in a transmitting-tele-
phone, of the mouth-piece, the diaphragm ar-
ranged behind the same and supported at its
edges, an elastic cushion arranged behind the
diaphragm at or around its center, a spring 75
arranged to press upon said cushion and force
it against the diaphragm, and means for ad-
justing the tension of said spring, substan-
tially as and for the purposes set forth.

5. In a transmitting-telephone, the combina-
tion of a diaphragm supported elastically at
separate points around its edge, the interven-
ing portions of its edge being left unconfin-
ed and free to vibrate, with a damper to control
its vibration, consisting of an elastic cushion 80
at its center and an adjustable spring arranged
to press against said cushion, substantially as
set forth. 85

6. The combination of the diaphragm, the
electrode E borne thereby, and the electrode 90
F, with its holder a, the spring or springs b b,
slide c, the lever e, the screw f, and the spring
g, forming an adjusting device for the elec-
trode F, substantially as set forth.

In witness whereof I have hereunto signed 95
my name in the presence of two subscribing
witnesses.

SAMUEL RUSSELL.
